(57) **CLAIM**

The ornamental design for a tool bag, as shown and described.

DESCRIPTION

FIG. 1 is a perspective view of the tool bag showing my new design;

FIG. 2 is a perspective view thereof from another angle;

FIG. 3 is a perspective view thereof from a different angle;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of a portion indicated with numeric 10 in FIG. 3.

FIG. 11 is a cross-sectional view of the numeral 11 in FIG. 4, the cross-sectional view on the right and the left sides;

FIG. 12 is a partially exploded perspective view thereof;

FIG. 13 is a perspective view of the tool bag when the tool bag is in use;

FIG. 14 is a perspective view of the tool bag when it is folded;

FIG. 15 is a top exploded view of the tool bag; and,

FIG. 16 is its exploded bottom view of the tool bag.

The broken lines shown in the drawings are included for the purpose of illustrating portions of the tool bag that form no part of the claimed design.
